UNITED STATES PATENT OFFICE.

SHERMAN A. HATHORNE, OF WAUKEGAN, ILLINOIS, ASSIGNOR TO CHICAGO HARDWARE FOUNDRY COMPANY, OF NORTH CHICAGO, ILLINOIS, A CORPORATION OF ILLINOIS.

BUTTER CUTTER AND THE LIKE.

1,413,223.

Specification of Letters Patent. Patented Apr. 18, 1922.

Application filed May 19, 1921. Serial No. 470,791.

To all whom it may concern:

Be it known that I, SHERMAN A. HATHORNE, a citizen of the United States of America, and a resident of Waukegan, in the county of Lake, State of Illinois, have invented certain new and useful Improvements in Butter Cutters and the like, of which the following is a specification.

This invention relates to that class of slicing machines in which a block or mass of butter or the like is fed step by step to a dividing head adapted to effect longitudinal division of the mass and then into the path of a slicing cutter to be transversely divided into slices or sections of the desired size and thickness. The objects of the present improvement are:—

To provide a structural formation and arrangement of parts of the intermittent or step by step feeding mechanism adapted for operative engagement with the shaft or rod of the feeding plunger, and by means of which an accurate and readily adjustable feeding movement of said plunger is effected with a cutting of the slices or sections to a predetermined thickness.

To provide a simple and effective arrangement of parts for tensioning the severing wires by which the mass of material is longitudinally divided, all as will hereinafter more fully appear.

In the accompanying drawings:—

Fig. 1, is a plan view of a butter cutting machine embodying the present invention.

Fig. 2, is a side elevation.

Fig. 3, is a detail bottom plan.

Fig. 4, is a front elevation.

Fig. 5, is a detail longitudinal section on line 5—5, Fig. 6.

Fig. 6, is a detail transverse section on line 6—6; Fig. 5.

Fig. 7, is a detail rear elevation illustrating the attaching means of the dividing cross wires of the machine.

Fig. 8, is a detail plan view of the attaching means of the slicing wire to the lever or sweep of the machine.

Like reference numerals indicate like parts in the several views.

Referring to the drawings, 1 designates the holding trough for the block of butter or other material operated on. Said trough is of the usual V shape in cross-section and

is carried by a skeleton supporting frame or base 2, having the usual central supporting hub or pedestal 3 and posts and blocks formed to afford bearings and supports for the different parts and shafts of the machine.

4 designates the usual rectangular frame secured to the front end of the frame 2 in operative relation to the trough 1, and provided with diagonal crossed wires 5 by which the material operated on as it passes from the trough 1 is divided into longitudinal sections. Said wires 5 are secured to the frame 4 preferably by means hereinafter described.

6 designates the movable plunger of the machine, preferably of the usual rectangular shape and adapted to have longitudinal movement in the holding trough 1, to force the material through the opening of frame 4, to be severed longitudinally by the cutter wires 5, and to such end said plunger is provided with a rearwardly extending rod or shaft 7 moving in guides on the base 2, and having an operating handle or knob 7' at its rear end as shown.

8 designates the primary driving shaft of the machine, arranged in transverse bearings at the rear of the frame 2, and provided at one end with a hand crank 8' or other usual operating means.

9 designates a cam fixed on the shaft 8 and adapted to impart a positive forward movement to the step by step feeding mechanism now to be described.

10 designates a rock arm pivoted at its lower end on the frame 2 in a plane below the axis of the shaft 8 and adapted to have operative bearing intermediate its height with the cam 9 aforesaid.

11 designates a screw mounted in the frame 1 and adjustable longitudinally in the paths of the upper portion of the rock arm 10 to regulate the distance of the arm 10 from the cam 9, and the consequent amount of movement which said cam will impart to said rock arm on each revolution.

12 designates a spring arranged intermediate the frame 2 and the rock arm 10 and adapted to impart a rearward movement to said rock arm and maintain the same in operative relation to the cam 9 aforesaid.

13 designates a link preferably of a yoke

55

60

105

form, arranged longitudinally and having its forward end pivotally connected to the upper end of the rock arm 10. At its rear end the link 13 carries the intermittent grip 5 member of the step by step feed mechanism arranged as follows.

- 14 designates the grip member above referred to, arranged vertically and pivoted at its mid-height to the rear end of the link 13. 10 The number 14 is formed at its upper end with a curved handle 15 for convenient manual actuation, and at its lower end is provided with an obliquely arranged eye 16 adapted to encircle the plunger rod 7 and 15 have gripping engagement therewith in its forward longitudinal movement. With the described arrangement of the grip member 14, its obliquely arranged eye 16 in an initial forward movement of the member is 20 adapted to grip or engage the plunger shaft 7 to cause a forward movement of the same depending on the amount of forward movement imparted to the rock arm 10 by the cam 9.
- 25 17 designates a forwardly extending arm intermediate the height of the grip member 14, and 18 designates a spring arranged intermediate of said arm 17 and the link 13 and adapted to yieldingly hold the eye 16 30 of the grip member 14 in the gripping engagement with the plunger rod 7, above described.
- 35 19 designates a holding or pawl member, preferably arranged in a transverse direction and pivoted at one end to the frame 2 and formed intermediate its length with an oblique orifice 20, similar to the oblique eye 16 above described, and adapted to encircle the plunger rod 7 and have intermittent 40 gripping or holding engagement with said rod to prevent rearward movement of the same while permitting a forward movement under the influence of the grip member 14 above described.
- 45 21 designates a spring arranged intermediate the frame 2 and the pawl member 19 and adapted to yieldingly hold the same in holding engagement with the plunger rod 7 aforesaid.
- 50 22 designates an upturned horn or finger piece on the free end of the pawl member for the convenient manual actuation of same to the release condition.
- 55 In the present construction the release of the feeding eye 16 and the holding orifice 20 from their gripping engagement with the plunger rod 7 to permit a free backward shift of the plunger to the rear of the trough 1, on the completion of the cutting operation, is readily attained by the fingers of the operator pressing the handle 15 in a rearward direction and the handle 22 in a forward direction, while moving the plunger and its rod 7 to the desired retracted position. With the plunger rod 7 attaining the

limit of a forward movement any further feed of the same is prevented by the hub or knob 7 contacting with and moving the holding pawl 19 into the inactive position just described.

70

The dividing wires or strands 5 heretofore referred to are in the present improvement formed from a single length of wire, the respective ends of which pass through orifice 23, in the frame 4 and are secured in place 75 by holding pins 24 engaging eyes on said wire ends as shown in Fig. 7. From the orifice 23 the wires extend centrally across the frame 4 to and around shoulders 25 at the other sides of the frame 4, and end in a 80 loop adapted for engagement with a tensioning mechanism as follows.

75

26 designates a head having sliding movement in a longitudinal direction on the underside of the frame 2 and formed with an orificed lug 27 around which the wire loop above described has engagement, as shown in Fig. 3.

85

28 designates a tensioning screw passing through the aforesaid orificed lug 27 and screwing into a screw-threaded orifice in a projection 29 on the frame 2 and in its adjustment is adapted to effect the desired tensioning of the cutting wires 5 of the machine.

95

30 designates the usual movable cutter wire of the machine, arranged in a transverse plane immediately in front of the frame 4 aforesaid, and carried by a revolvable sweep or carrying frame now to be 100 described.

100

31 is a shaft portion journalled longitudinally in the frame 2 and operatively connected at its rear end to the primary shaft 8 by a pair of bevel gears 32, or other usual 105 means.

105

33 designates an angular extension of the shaft portion 31, formed at its free end with a rear prong 34, as shown, and as usual in the present type of machines. Such rear prong is adapted to support one end of the aforesaid cutter wire 30, with the other end of said wire attached to the shaft portion 31 as shown.

110

The attachment of the wire 30 to the 115 prong 34 is preferably in an adjustable manner in order to effect the proper tensioning of said wire, and in the construction shown:

115

35 designates a toggle plate pivoted to 120 the prong 34 and having connection with an end of the wire 30, so that when swung into its set position shown in Fig. 8, it will effect the required tensioning of said wire.

120

Having thus fully described my invention, 125 what I claim as new and desire to secure by Letters Patent is:

125

1. The combination of a frame, a plunger rod slidingly mounted in said frame, a rock arm pivoted at one end in said frame, a 130

130

shaft journalled in said frame and having a cam adapted to operatively engage said rock arm, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward stroke of the parts, and means for engaging said rod and holding the same from retrograde movement.

2. The combination of a frame, a plunger rod slidingly mounted in said frame, a rock arm pivoted at one end on said frame, a shaft journalled in said frame and having a cam adapted to engage and move the rod arm in a forward direction, a spring engaging said rock arm and adapted to move the same in a rearward direction, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward stroke of the parts, and means for engaging said rod and holding the same from retrograde movement.

30

3. The combination of a frame, a plunger rod slidingly mounted in said frame, a rock arm pivoted at one end on said frame, a shaft journalled in said frame and having a cam adapted to engage and move the rod arm in a forward direction, a spring engaging said rock arm and adapted to move the same in a rearward direction, an adjustable screw arranged in the path of the rock arm and adapted to regulate the rearward stroke of the same, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward stroke of the parts, and means for engaging said rod and holding the same from a retrograde movement.

4. The combination of a frame, a plunger rod slidingly mounted on said frame, a rock arm pivoted at one end in said frame, a shaft journalled in said frame and having a cam adapted to operatively engage said rock arm, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward stroke of the parts and a pawl member pivoted on the frame and formed with an oblique orifice encircling the

plunger rod and adapted to have gripping engagement therewith and hold the same against retrograde movement.

5. The combination of a frame, a plunger rod slidingly mounted in said frame, a rock arm pivoted at one end on said frame, a shaft journalled in said frame and having a cam adapted to engage and move the rod arm in a forward direction, a spring engaging said rock arm and adapted to move the same in a rearward direction, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward stroke of the parts, and a pawl member pivoted on the frame and formed with an oblique orifice encircling the plunger rod and adapted to have gripping engagement therewith and hold the same against retrograde movement.

6. The combination of a frame, a plunger rod slidingly mounted in said frame, a rock arm pivoted at one end in said frame, a shaft journalled in said frame and having a cam adapted to engage and move the rod arm in a forward direction, a spring engaging said rock arm and adapted to move the same in a rearward direction, an adjustable screw arranged in the path of the rock arm and adapted to regulate the rearward stroke of the same, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward stroke on the parts, and a pawl member pivoted on the frame and formed with an oblique orifice encircling the plunger rod and adapted to have gripping engagement therewith and hold the same against retrograde movement.

7. The combination of a frame, a plunger rod slidingly mounted in said frame, a rock arm pivoted at one end in said frame, a shaft journalled in said frame and having a cam adapted to engage and move the rod arm in a forward direction, a spring engaging said rock arm and adapted to move the same in a rearward direction, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward stroke of the parts, and a pawl member pivoted on the frame and formed with an oblique orifice encircling the plunger rod and adapted to have gripping engagement

- therewith and hold the same against retrograde movement, the grip member and the pawl member having projecting horns or extensions for convenient manual operation.
- 5 8. The combination of a frame, a plunger rod slidingly mounted in said frame, a rock arm pivoted at one end on said frame, a shaft journalled in said frame and having a cam adapted to engage and move the rod
- 10 arm in a forward direction, a spring engaging said rock arm and adapted to move the same in a rearward direction, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a forward
- 15 stroke of the parts, a pawl member pivoted on the frame and formed with an oblique orifice encircling the plunger rod and adapted to have gripping engagement therewith and hold the same against retrograde move-
- 20 ment, and a spring interposed between the frame and the pawl member and adapted to yieldingly hold said pawl member to its engagement with the plunger rod.
9. In a slicing machine, the combination
- 25 of a frame and an associated material holding hopper, a rectangular frame arranged at the forward end of said trough and provided with crossed cutter wires, a feeding plunger arranged in said trough and having
- 30 a carrying rod, a primary shaft journalled in said frame and carrying a cam, a shaft journalled longitudinally in said frame and operatively connected at its rear end to said primary shaft, an angular
- 35 extension at the forward end of the longitudinal shaft, a cutter wire carried by said shaft and extension in adjacent relation to the crossed wires aforesaid, a rock arm pivoted at one end in said frame and having
- 40 operative engagement with the cam aforesaid, a link pivoted to the far end of the rock arm and extending rearwardly of the same, a grip member pivoted to the rear end of said link and having an eye encircling
- 45 the plunger rod, the opening of said eye being arranged oblique to said rod and adapted to have gripping engagement therewith in a forward stroke of the parts, and means for engaging said rod and holding the same
- 50 from retrograde movement.
10. In a slicing machine, the combination
- 55 of a frame and an associated material holding hopper, a rectangular frame arranged at the forward end of said trough and pro-
- 60 vided with crossed cutter wires a feeding

plunger arranged in said trough and having a carrying rod, a primary shaft journalled in said frame and carrying a cam, a shaft journalled longitudinally in said frame and operatively connected at its rear end to said 65 primary shaft, an angular extension at the forward end of the longitudinal shaft, a cutter wire carried by said shaft and extension in adjacent relation to the crossed wires aforesaid, a rock arm pivoted at one end 70 in said frame and engaging the aforesaid cam to receive a forward movement therefrom, a spring engaging said rock arm and adapted to move the same in a rearward direction, a link pivoted to the free end of the 75 rock arm and extending rearwardly of the same, a grip member pivoted to the rear end of said link and having an eye encircling the plunger rod, the opening of said eye being arranged oblique to said rod and adapted 80 to have gripping engagement therewith in a forward stroke of the parts, and means for engaging said rod and holding the same from retrograde movement.

11. In a slicing machine, the combination of 85 a frame and an associated material holding hopper, a rectangular frame arranged at the forward end of said trough and provided with crossed cutter wires, a feeding plunger arranged in said trough and having a 90 carrying rod, a primary shaft journalled in said frame and carrying a cam, a shaft journalled longitudinally in said frame and operatively connected at its rear end to said primary shaft, an angular extension at the 95 forward end of the longitudinal shaft, a cutter wire carried by said shaft and extension in adjacent relation to the crossed wires aforesaid, a rock arm pivoted at one end in said frame and engaging the aforesaid cam to receive a forward movement therefrom, a spring engaging said rock arm and adapted 100 to move the same in a rearward direction, a link pivoted to the free end of the rock arm and extending rearwardly of the same, a grip member pivoted to the rear end of said link and having an eye encircling the plunger rod, the opening of said eye being arranged oblique to said rod and adapted to have gripping engagement therewith in a 105 forward stroke of the parts, an adjustable screw arranged in the path of the rock arm and adapted to regulate the rearward stroke of the same, and means for engaging the plunger rod and holding the same from 110 retrograde movement.

Signed at North Chicago, Ills., this 12th day of May, 1921.

SHERMAN A. HATHORNE
